CLAIM

The ornamental design of headphones, as shown and described:

DESCRIPTION

A portion of this patent document contains material which is subject to copyright protection. The copyright owner has no objection to the facsimile reproduction by anyone of the patent document or the patent disclosure, as it appears in the Patent and Trademark Office patent files or records, but otherwise reserves all copyrights whatsoever.

FIG. 1 is a perspective view of headphones according to my new design;

FIG. 2 is a front elevation view thereof;

FIG. 3 is a top plan view thereof;

FIG. 4 is a left side elevation view of a portion of the headphones;

FIG. 5 is a right side elevation view of a portion of the headphones;

FIG. 6 is a back elevation view thereof; and,

FIG. 7 is a bottom plan view thereof.

The Broken line showings throughout the views are for illustrative purposes only and form no part of the claimed design.
